UNITED STATES PATENT OFFICE.

CARL A. MEILICKE, OF CHICAGO, ILLINOIS.

MOVABLE-READING-LENS HOLDER.

1,149,383.

Specification of Letters Patent. Patented Aug. 10, 1915.

Application filed February 19, 1914. Serial No. 819,670.

To all whom it may concern:

Be it known that I, CARL A. MEILICKE, a subject of the King of Great Britain, residing at Chicago, in the county of Cook and State of Illinois, have invented certain new and useful Improvements in Movable-Reading-Lens Holders, of which the following is a specification.

My invention has for its general object to provide an effective, adjustable magnifying-reading-glass mounting for machines having a long reading line, (as is the case in calculating machines and the like,) wherein the reading lens is mounted for pivotal movement in one direction to place it in or remove it from position for use, and is slidably adjustable in another direction to vary its reading position.

A further object of my invention is to provide a reading glass mounting and setting wherein the lens, relatively large and shaped for effective magnifying qualities covering a relatively large reading field, may be adequately protected so that it is not liable to fracture or damage due to its positioning movements, or to expansion and contraction.

Other objects of my invention will be apparent to those skilled in the art from the following description taken in conjunction with the accompanying drawings in which—

Figure 1 is a front elevation of a calculating machine equipped with my invention; Fig. 2 is a side elevation with parts broken away; Fig. 3 is an enlarged section on line 3—3 of Fig. 1. Fig. 4 is an enlarged sectional detail of the roller and spring mechanism; Fig. 5 is an enlarged detail of a lens retaining clip and contiguous parts; Fig. 6 is an end elevation, with parts broken away, showing a friction grip mechanism associated with the reading glass rock shaft; Fig. 7 is a section through the same. Fig. 8 is a perspective view showing a shaft supporting clip.

In the embodiment of my invention the reading glass or lens, generally indicated at 10, is mounted in a suitable frame rim 11, from which project two arms 12—12 slidably engaging the longitudinal slide bar 13. This bar has at least one flat face, and is preferably of polygonal cross section, the engagement of the arms with the flat-faced or polygonal bar being preferably relatively loose, so as to allow some pivotal lost motion

between the lens carrying frame and the slide bar. The slide bar is mounted to be rocked in end bearings, to enable the lens carrying frame to be raised and lowered, out of and into the reading plane, and the sliding movement of the frame along the slide bar enables it to be positioned in the precise reading position desired.

When in lowered or operative position a portion of the lens holding frame relatively remote from the slide bar has a gravity-maintained bearing upon a slide way; and such co-operative relation is effected between the means employed for restricting the pivotal throw of the flat-faced slide bar 13 and the bearing members remote from the pivotal axis of said rod, that the lens frame may be given the capacity for freely sliding upon the bar 13 without cramping or binding due to engagement of arms 12 with the bar 13. Thus in the particular construction shown, the lens frame 11 is provided at its lower end with a boss 15 in which is mounted the guide roller structure 16 providing an anti-friction roller 17 for coaction with a slide way 18 suitably mounted on the frame of the machine. The boss 15 is preferably bored and counter-bored to provide a recess 19—19' of two diameters, and the roller 17 is mounted in the head 20 from which extends the stem 21—21' of two diameters to correspond with the diameters of the counter-bore. A spring 22 interposed between the base of the bore of larger diameter and the base of the larger diameter of the stem presses the roller-head outward, giving the roller-head a resilient capacity for reciprocation limited, in the specific construction shown, by the throw of the slot 23 in the stem relative to a screw 24 mounted on the boss, said screw and slot also preventing the roller-carrying head from rotating. The position of the slide-way 18 on the machine frame is such that when the lens frame is brought to operative or reading position gravity tends to maintain the contact between the roller 17 and its slideway.

The rotative or pivotal movements of the slide bar 13 are opposed by a friction device, preferably adjustable as the frictional grip. Thus, in the particular construction shown, the slide bar 13 has cylindrical end portions 13' (Fig. 7) engaged in brackets 26, mounted on the frame of the machine, preferably in adjustable fashion by engagement 110

of screws 27 in the slots 28 in the bases of the brackets 26. Beyond one of said brackets 26 a bearing part 13' of the bar has mounted thereon a friction head 30, preferably provided with a leather or other frictional surface covering 31 (Figs. 6 and 7). A brake band or split ring 32 encompasses the friction disk and is adjustable as to tension by a suitable screw 33 taking through its two split limbs. A pin 35 projects from the brake band and engages in the bracket 26, so that the band exerts a constant resistance to pivotal movement of the slide bar 13. A pin 36 carried by the disk 30 is arranged to coact with the upper edge of the bracket 26 to act as a stop against overthrowing of the lens-carrying frame when the latter is raised to out-of-use position.

The particular machine with which I have shown the parts employed for embodiment 20 of my present invention to be connected, is a calculating machine, and I will herein describe the use of my invention with respect to that particular application thereof, although it will be understood that the present invention is not limited to the character of the machine to which the reading glass is applied, and that many changes might be made in the specific embodiment thereof 25 within the spirit of the present invention and the scope of the appended claims for utilization of the invention in connection with other machines. By reference to some 30 of the characteristics of the calculating machine, however, some of the advantages of my present invention will be accentuated.

The calculating machine shown provides a frame or casing 40 carrying the lens-mountings and having a sight opening protected by a glass 41 set in a rim frame of 40 which the slide way 18 may form a part. Beneath the reading glass there is displayed a fixed scale or index 42, having a reading line opening 43 through which is displayed 45 a single line of figures, which is one of the many horizontal lines carried by a rotatable chart-drum 44. It is for easy reading of the indicia upon the fixed and movable charts or scales that the magnifying lens is primarily provided as the figures are necessarily small.

It will be apparent that unimpeded dropping of the relatively heavy lens in its frame so that its roller 17 might forcibly strike the 55 slideway 18 constituting part of the retaining frame for the glass 41 would be very apt to break the glass 41 and possibly the reading glass, and to bend, dent or improperly jar the machine casing, and for these 60 reasons, among others, the frictional restraint is preferably always imposed upon the pivotal movements of the slide bar 13. Furthermore as it is decidedly advantageous to have the magnifying lens large enough to 65 cover a considerable longitudinal area of

the machine, for rapid reading work, the lens has to be relatively wide, thick and heavy and it might be damaged by differences in expansion and contraction with respect to its holding frame or by impact of 70 the frame against the end stops when the glass is slid from end to end of the machine, and for these reasons, among others, I provide a special lens mounting which I have found to be very advantageous, particularly 75 with respect to the relatively large and thick lens employed.

The lens is preferably of somewhat ovate, plano-convex form having a flat bottom chord as at 10'.

The lens frame 11 is constructed to provide at 11^a a square bearing for the squared, and relatively thick, straight edge 10' of the glass, and throughout the balance of its perimeter where it engages the glass, it is preferably beveled or concaved as at 11^b (see Fig. 3) to engage smoothly the convex surface of the lens along its border.

Glass retaining clips 11^c are secured to the under side of the frame, each clip being preferably made of spring metal shaped to provide a base 11^d, secured directly to the metal lens-frame, and a head 11^e arched somewhat (see Fig. 3) for engagement at its tip or edge only with the glass, and preferably arranged so that its gripping edge lies beneath the inner perimeter of the lens rim 11. The glass, therefore, has a certain capability of expanding with the shoulder or flat surface 10' as a base, the beveled or wedge-action engagement between the convex border of the glass and rim at all other points permitting some come-and-go to which the spring clips may slightly yield. Such action of course is very slight, but I find that 100 the construction described adequately prevents marginal chipping or checking of the glass under expansion and contraction. Also the support of the glass from below upon the slightly springy clips gives a 110 slight but effective resiliency to the mounting in the direction of the thickness of the lens, while the securing of the glass against bodily displacement is simply attained.

The operation of the device will be as follows: When the glass is not to be used, it is lifted, the bar 13 turning against the resistance of the friction plate until pin 36 bears on the top edge of its adjacent bracket 26 as a positive stop. When the glass is returned to reading position, it carries with it in rotation the slide-bar 13, and the glass is brought down not only until the anti-frictional roller 17 touches the slide way 18, but it is depressed farther, until the boss 15 has traveled downward to the extent permitted by the play of screw 24 in slot 23, against the resistance of spring 22, thereby turning the bar 13 through a slight degree of angular displacement greater than that 130

which would be effected by the movement of the lens frame only to the position to which the lens frame is finally to occupy. In consequence, when the downward pressure on the lens frame is released and the spring 22 lifts the lens frame back slightly, to its position for use, the apertures in the arm 12 are loosened on the bar 13 due to the slight pivotal lost motion between the 10 arms and bar, and may slide freely without any clutch action on the bar, the weight of the lens and frame being borne jointly by the bar 13 and the slideway 18. It will be observed of course that the range of throw 15 allowed by slot 23, for over-depression of the lens frame, must be properly proportioned so that the spring return movement does not reversely bind the arms 12 upon the bar 13, but moves said arms rotarily with respect to the bar only within the slight range 20 of lost motion left between the apertures in said arms 12 and the bar 13.

I find in practice that the construction above described is of very great advantage, 25 giving to the lens carrier a perfect freedom of movement in sliding which facilitates rapid and accurate manipulation of the lens. The frictional grip of the brake band on the friction disk is generally best regulated so 30 as to hold the bar 13 against slippage in any pivotal position to which it may be moved, so to avoid any possibility of the lens falling to reading position, however carelessly it may be handled. The lens mounting de- 35 scribed may, of course, be varied, according to the requirements of the lens, as may other details of construction, but I have found in commercial construction that the lens holding arrangement herein described, is very 40 satisfactory in its prevention of edge cracking, checking, or breakage of the lens.

The same equipment of bar, lens frame, etc., shown herein as attached to a calculating machine, may be used on other machines, 45 with only changes in proportions and incidental details, and the proper parts are of course subject to separate sale as an attachment set for any machine where a horizontally slidable reading lens is desirable.

50 Having thus described my invention, what I claim with a view and desire to secure by Letters Patent is:—

1. The combination with a body, of separated supports, a slide bar mounted to rock in said supports, a guide way carried by said body paralleling said slide bar, and a lens frame mounted to rock with and slide on said bar and when in position for use to receive bearing from said slide way,

55 2. The combination with a body, of separated supports, a slide bar rotatably mounted at its ends in said supports, a guide way on said body paralleling said slide bar, a lens frame slidably mounted at one side on said bar, and a roller carried by the oppo-

site side of the lens frame for coöperation with the guide when the lens frame is in position for use.

3. The combination with a body, of separated supports, a slide bar mounted to rock in said supports, a guide way carried by said body paralleling said slide bar, a lens frame mounted to rock with and slide on said bar and when in position for use to receive bearing from said slide way and resilient means to permit movement of said lens frame past its said position of bearing on the slide-way for resilient restoration to the said position, thereby to prevent cramping of the lens frame on the slide bar. 75

4. In a structure of the character described, the combination of a body, a slide bar mounted to rock thereon, a lens frame mounted on said bar with some pivotal lost motion, to rock therewith and to slide thereon; a slide way member for affording bearing to the lens frame remote from the slide bar, resilient means to permit movement of the lens frame beyond the normal position defined by said slide bar for spring return thereby to prevent cramping of the lens frame on the slide bar and friction means opposing rocking movements of the slide bar. 85

5. The combination of a body providing separated supports and a slide way remote therefrom, a flat-faced slide bar mounted to rock in said supports, a lens frame mounted on said bar with some pivotal lost motion to rock therewith and to slide thereon, and spanning the space between the slide bar and the slide way, and a resilient bearing member for coaction with said slide way carried by said lens frame. 95

6. The combination of a body providing separated supports and a slide way remote therefrom, a flat-faced slide bar mounted to rock in said supports, a lens frame mounted on said bar with some pivotal lost motion to rock therewith and to slide thereon, and spanning the space between the slide bar and the slide way, a resilient bearing member for coaction with said slide way carried by said lens frame, and means for opposing rocking movements of said slide bar. 105

7. In a machine of the character described the combination of a body providing a slide way, supports spaced apart therefrom and from each other, a flat faced slide bar mounted in said supports to rock 120 therein and arranged parallel to the slide way, a lens frame mounted on said bar to rock therewith and to slide thereon, and spanning the space to said slide way, a friction means for opposing rocking movements of said slide bar, and an antifrictional roller for bearing on said slide way, carried by said lens frame and yieldably mounted thereon for the purpose described. 125

8. The combination of a lens having a 130

perimeter formed of a continuing curve and a flattened chord, a lens frame having a flat portion to receive the chord and other portions thereof arranged to interfit with the convex surface of the lens, and fastening means holding said lens with its convex surface against said curved portions of the frame and its chord portion upon the flat part of the frame.

10 9. The combination of a lens having a perimeter formed of a continuing curve and a flattened chord, a lens frame having a flat portion to receive the chord and other por-

tions thereof arranged to interfit with the convex surface of the lens, and spring clips 15 holding said lens with its convex surface against said curved portions of the frame and its chord portion upon the flat part of the frame.

In testimony whereof I hereunto set my 20 hand in the presence of two witnesses.

CARL A. MEILICKE.

In the presence of—
STANLEY W. COOK,
MARY F. ALLEN.
